UNITED STATES PATENT OFFICE.

WILLIAM T. SMITH, OF PHILADELPHIA, PENNSYLVANIA.

DESIGN FOR A WOVEN FABRIC.

SPECIFICATION forming part of Design No. 35,162, dated October 1, 1901.

Application filed September 6, 1901. Serial No. 74,541. Term of patent 3½ years.

To all whom it may concern:

Be it known that I, WILLIAM T. SMITH, a citizen of the United States, residing in Philadelphia, Pennsylvania, have invented and produced a certain new and original Design for a Woven Fabric, of which the following is a specification.

My design is shown in the accompanying drawing, which represents sufficient of the pattern to illustrate such design, the remainder being simply a repetition of what is shown.

The said design comprises as its main features the ornamentation of the central portion 1, the border 2, and the ground 3 between said central portion and the border. The central portion 1 comprises a centrally-located octagonal figure 4, a similarly-shaped figure 5, located at one end of said central portion, and a border 6, surrounding said central portion 1, said border being composed of a series of parallel lines connected together and extending in various directions and enclosing a series of detached figures. At one side of the central octagonal figure 5 a triangular figure 7 is arranged, having a notched base, and disposed over the main surface of said central portion 1 are a series of smaller triangular-shaped figures 8 and lozenge-shaped figures 9, arranged as shown, together with a series of S-shaped figures. The bor-

der 2 includes two bands 10, having an ornamentation made up of balls connected by ribbon-like members, and two bands 11, made up of a series of diamond-shaped figures of different size arranged in regular order. Between these two latter bands is a body portion made up of a series of figures, as shown.

The ornamental ground portion of the fabric between the central portion 1 and border 2 contains a pair of figures 7, a series of figures 12, triangular in shape and set in various positions, and the figures 13, 14, 15, 16, and 17. Interposed between these several figures in different positions are a series of detached figures of various shapes.

The design is applicable to table-covers, drapery, and hangings generally.

Having thus described my invention, I claim and desire to secure by Letters Patent—

The design for a woven fabric, substantially as described and as shown in the accompanying drawing.

In testimony whereof I have signed my name to this specification in the presence of two subscribing witnesses.

WM. T. SMITH.
